UNITED STATES PATENT OFFICE.

ANTOINE PROSPER PLAUT, OF CLEVELAND, OHIO, ASSIGNOR OF ONE-HALF TO RICHARD B. SHERIDAN, OF CLEVELAND, OHIO.

CARBURETER.

1,204,901.

Specification of Letters Patent. Patented Nov. 14, 1916.

Application filed November 4, 1914. Serial No. 870,280.

To all whom it may concern:

Be it known that I, ANTOINE PROSPER PLAUT, a citizen of the Republic of France, residing at Cleveland, in the county of 5 Cuyahoga and State of Ohio, have invented a certain new and useful Improvement in Carbureters, of which the following is a full, clear, and exact description.

This invention is an improved carbureter 10 adapted for use in connection with an internal combustion motor to produce the explosive charges required by the motor.

The principal object of the invention is to produce substantial uniform mixture of air 15 and fuel vapor of any desired proportions under all of the varying conditions of use of the motor, especially on an automobile.

Another object of the invention is to produce a carbureter which will render the 20 starting of the motor easier.

Another object is to produce a cheap carbureter which will contain few parts, and none which are liable to get out of order in use.

25 The invention is shown in the drawings and hereinafter described and definitely pointed out in the appended claims.

In the drawing Figure 1 is a side elevation of a carbureter embodying the invention in what is now believed to be its best and simplest form. Fig. 2 is a sectional plan view in the plane indicated by line A—B on Fig. 3. Fig. 3 is a central vertical sectional view of the carbureter in the plane 30 indicated by line C—D on Fig. 2. Fig. 4 is a top plan view of the Venturi tube which is a part of the carbureter shown in the preceding figures. Fig. 5 is an elevation partly sectioned of an alternative form of the invention. Fig. 6 is a vertical sectional view of the tubular body member and associated parts showing another modification of the invention. Fig. 7 is a side elevation of a part of the carbureter shown in Fig. 5, designed particularly to show the air valve mechanism. Figs. 8 and 9 are respectively sectional views in the planes of lines E—F and G—H on Fig. 7. Fig. 10 is a sectional view in the plane of line J—K on Fig. 7; and Fig. 11 is a detached view of the two air valves which are also shown in Fig. 10.

The carbureter includes a tubular body member 1 which may be flanged at its upper end to facilitate its connection with the 55 inlet manifold of the motor; and when, in use, this tubular body member is open at its lower end for the admission of air; and in the upper end of this tube is a throttle valve 9 which may be of any suitable form, as, for 60 example, a butterfly valve, as shown. It is one of the advantageous characteristics of this tubular body that it contains no obstructions, such as a nozzle, to modify in an indeterminate way the rate of flow of air 65 through it.

10 represents a constant level fuel reservoir,—that is to say, an ordinary float valve chamber adapted to maintain the fuel level therein in the plane indicated by the line 70 11—11 found on Figs. 1 and 3 and 5 and 6.

2 represents a tube which is fitted within the tube 1; and 4 represents an annular expansion chamber between the two tubes 1 and 2. In the construction shown in Figs. 75 1, 2 and 3, the tube 2 is a Venturi tube; and the fuel expansion chamber is formed by means of a circumferential groove cut in the outer wall of this tube. In the construction shown in Figs. 5 and 6 the tube 2 does 80 not have the Venturi form, and the expansion chamber lies above an outwardly projecting flange 2^a on the lower end of the tube 2. As shown in Fig. 5 this chamber has no top wall, while as shown in Fig. 6, there is a 85 top wall formed by the flange 2^b. In all cases the outer wall of this annular chamber is formed by the outer tubular body member 1. In open and unrestricted communication with this fuel reservoir is a nozzle 5 90 from which fuel is delivered into this annular expansion chamber.

The several embodiments of the invention shown are constructed with special reference to making the starting of the engine 95 easy; and in order to secure this result, the bottom of the expansion chamber and the discharge end of the nozzle 5 are both below the fuel level, as indicated by line 11—11. As a result of this, when the engine is idle, some liquid fuel will flow into and accumulate in the said expansion chamber. In the construction shown in Figs. 1, 2, 3 and 6 this nozzle communicates directly

with the annular expansion chamber. In the construction shown in Fig. 5 the nozzle 5 discharges into a laterally extended tube 4^c which is in open communication with 5 said annular expansion chamber, and is in effect a part of it. In all cases this annular expansion chamber communicates freely in an upward direction with the interior of the tubular body member 1. In the construction 10 shown in Figs. 1, 2 and 3, for example, there are a plurality of small inclined holes 7 extending from the annular expansion chamber diagonally upward and inward through the wall of the Venturi tube,—their 15 discharge ends being above but closely adjacent the most restricted part or throat of said Venturi tube. In the construction shown in Fig. 6 an annular row of vertical holes 7 are formed through the flange 2^b 20 and it is through these holes that communication is established upward from the annular expansion chamber to the tubular body member. In the construction shown in Fig. 5 this upward communication between the 25 annular expansion chamber and the interior of the tubular body member is unrestricted; that is to say, there is no overhanging top wall to this expansion chamber; and therefore there is in effect an open annular slot 30 which establishes communication between the expansion chamber and interior of the body tube.

6 represents an air tube which, when the device is in operation, communicates at its 35 inner end with the annular expansion chamber, and at its outer end is in open communication with the atmosphere, at a point above the fuel level in the float chamber and annular expansion chamber. In each case, 40 however, a valve is provided by which to vary the effective area of the inlet to this air tube. In the construction shown in Figs. 1, 2, 3 and 6, a tubular valve 14 is screwed into the air tube, so that the most restricted 45 area of the air passage will be always as great as the area of the hole 14^a through this valve. The end 14^b of the valve, however, is made conical for engagement with a valve seat 6^a within the air tube; and one or more 50 holes 6^b are made in the air tube above this seat. By unscrewing the valve, it will be moved away from its seat 6^a, so that there may be delivered into the annular chamber more or less extra air which enters the air 55 tube through said holes 6^b and passes between the valve and its seat. In the construction shown in Fig. 5 the air tube 6 communicates at its upper end with the tubular valve chamber 15, in which, preferentially, 60 there are two tubular valves 16, 17, having stems 16^a, 17^a, which respectively project through opposite ends of the valve chamber, so that they may be adjusted to any required 65 position. In the wall of the valve chamber, for coöperation with the valve 16, is a longi-

tudinally extended slot 15^a. In the associated valve 16 is a circumferential slot 16^c of increasing width from one end to the other. By turning this valve, the effective size of the air inlet to said valve is increased 70 or diminished. In the valve chamber 15 is also a circumferential slot 15^b, and in the associated valve 17 is another circumferential slot 17^b. By turning the valve, one may increase or decrease the effective area of this 75 slot,—that is to say, the length of the open part thereof. It is not thought that two valves are necessary for varying the rate of flow of air through air tube 6 to the extent necessary for practical purposes, but they 80 may be used as shown. Both valves are tubular, and both communicate with the air tube 6 which discharges into the tube 4^c.

In constructing the described carbureter, in any form, the expansion chamber 4 must 85 be sufficiently large to enable the air entering the same, to break up and substantially atomize therein, the fuel also admitted to said chamber from nozzle 5. In a carbureter employing a Venturi tube as shown in Fig. 90 3, having a throat 11/16ths of an inch in diameter, this expansion chamber will be large enough for the purposes, if it has a capacity of .2 cubic inches. In said carbureter the aggregate area of the holes 7 must 95 be sufficient to allow the fuel and air which are drawn into the expansion chamber to escape therefrom at the same rate. In practice it has been found that the aggregate area of 100 these holes 7 should be about 23% of the area of the throat. It has also been found that entirely satisfactory results are attained if the combined area of the valve controlled inlets to the air tube, when the valve 14 is wide open, is about 55% of the total area of the 105 holes 7. These relative sizes have been chosen somewhat empirically, but as a result of considerable experiment, and with the particular view of permitting the use of a nozzle 5 having an opening large enough to insure that it may not be easily stopped up. But having determined these relative sizes and having determined what the diameter of the throat of the Venturi tube should be to give the desired rate of velocity flow through 110 it for a particular engine with which it is to be used, one may calculate with sufficient accuracy for practical purposes how large the nozzle opening should be to cause the device to produce under all the conditions of use, a mixture having any desired proportion of air and atomized liquid fuel. For example, if it is desired to produce a 25 to 1 mixture, it must be remembered that the degree of 115 vacuum in the expansion chamber 4 is only 45% of the degree of vacuum in the throat of the Venturi tube. This is because the area of the inlet to the air tube is 55% of the total area of the holes 7, wherefore, since 120 55% of the air drawn from such holes is sup- 125 130

plied by the air tube 6, the resulting vacuum in the expansion chamber must be 45% of that in the throat of the Venturi tube. If the fuel is six hundred times heavier than air, the air will flow 24.49 times as fast as said fuel; and if we wish to make a 25 to 1 mixture, we may use the following formula to determine the relative area of the throat of the Venturi tube and the area of the fuel nozzle.

$$\frac{25 \times 600 \times .45}{24.49} = 275.$$

That is to say, the area of the throat of the Venturi tube should be 275 times as great as the area of the hole through the nozzle.

When a carbureter constructed as above described is secured to an engine to which it is adapted, and the engine is in operation, air will rush rapidly through the Venturi tube. Likewise fuel will be drawn from the nozzle into the expansion chamber at a definite rate, dependent upon the velocity of said air, or, more directly, upon the degree of vacuum in the expansion chamber, which, in turn, is dependent upon the velocity flow of the air in the Venturi tube and the relative areas of the holes 7 and the inlet to the air tube 6. Likewise air will rush with great rapidity into the expansion chamber, and will substantially atomize the fuel therein. The mixture of air and fuel spray will flow through the holes 7, and in flowing will be more finely atomized, and will join and become thoroughly mixed with the air steam rushing through the Venturi tube. The proportions of air and fuel spray will remain constant at all engine speeds and under all loads, because the proportioning conditions are not changed by changes in the actual rate of flow of air through the Venturi tube.

It will be understood that different grades of fuel and different atmospheric conditions will cause small indeterminable variations in the values of some of the factors employed in calculation and will therefore cause some slight variations in the proportions of the ingredients of the explosive charges, but these may be compensated for, to the necessary practical degree, by adjusting the valve in the air tube.

The construction described is such also that when the engine is stopped there will be an accumulation of liquid fuel in the expansion chamber 4. When the engine is started, air rushing into the expansion chamber will atomize and carry away with it at each suction stroke a considerable quantity of this accumulated fuel, thereby producing a very rich mixture which will facilitate the starting of the engine. In a very short time, however, this accumulation of fuel will be used up, and after this, the carbureter will act normally, that is in the

manner heretofore described. To facilitate the starting of the engine, a very light self closing valve 19, as, for example, the butterfly valve shown in Fig. 3 may be provided at the inlet end of the body tube. When the engine is idle, this valve will close. When the engine is being started and is therefore turning over very slowly the vacuum created in said body tube will not be great enough to cause this valve to open much, if any. Therefore a disproportionately large part of the air which goes to the engine will come through the air tube 6 and the expansion chamber. When, however, the engine has got to running normally, the vacuum in the body tube will be so great that this valve will occupy substantially the wide open position shown by dotted lines in Fig. 3. When the engine is idling this valve will be more or less closed, depending upon the rate at which the engine is running. This will, of course, change the proportions of air and fuel, making the mixture richer, but that is of no importance because, as soon as the engine is running under any load, the self closing valve will be open; and so long as it is, the carbureter will furnish the explosive mixture of the desired proportions of fuel and air.

Having described my invention, I claim:

1. In a carbureter, the combination of a tube which, except for the throttle valve hereinafter mentioned, is normally unobstructed and is adapted for connection at its upper end with an internal combustion engine and contains an annular chamber which is always in communication with the interior of said tube through one or more unclosable passageways, a fuel nozzle discharging into said annular chamber, a valve controlled air tube discharging into said annular chamber, and a throttle valve in the first mentioned tube located well above the plane in which said passageways communicate with the interior of said tube.

2. In a carbureter, the combination of a body tube adapted for connection at its upper end with an internal combustion engine, an unobstructed inner tube fitted in said body tube,—there being between said tubes an annular chamber which communicates with the interior of said inner tube through an annular row of always open holes, a fuel nozzle discharging into said annular chamber, a valve-controlled air tube which at its inner end communicates with said chamber, and a throttle valve in the body tube above said inner tube.

3. In a carbureter, the combination of a body tube adapted for connection at its upper end with an internal combustion engine, an unobstructed ajutage fitted within said body tube, there being between said ajutage and body tube an annular chamber which communicates with the interior of

said ajutage through a plurality of always open holes whose discharge ends are closely adjacent to the throat of said ajutage, a fuel nozzle discharging into said annular chamber, a valve controlled air tube which discharges into said annular chamber, and a throttle valve in the body tube above the ajutage.

4. In a carbureter, the combination of a body tube adapted for connection at its upper end with an internal combustion engine, an unobstructed Venturi tube immovably fitted within said body tube and having in its outer periphery an annular groove which with a body tube forms an annular chamber, there being a plurality of always open holes leading from said chamber to the interior of said Venturi tube, and discharging into the same in a plane closely adjacent to the throat of said Venturi tube, a fuel nozzle discharging into said annular chamber, and an air tube which communicates at its inner end with said annular chamber.

5. In a carbureter, the combination with a constant level fuel reservoir, of a substantially vertical tube which is normally open at its lower end and is adapted for connection at its upper end with an internal combustion engine and which contains in its wall a chamber which is in open communication with the interior of said tube above the level of the fuel in said reservoir,—there being an open fuel duct connecting said chamber with said fuel reservoir, and an air tube which communicates at its inner end with said chamber and has its outer end above said fuel level.

6. In a carbureter, the combination of a constant fuel reservoir, a substantially vertical body tube which is open at the lower end and is adapted for connection at its upper end with an internal combustion engine, an inner tube fitted within said body tube, having in its outer periphery an annular groove which forms with the body tube an annular chamber whose bottom is below the fuel level in said reservoir, and which communicates with the interior of said body tube in a plane above said fuel level, a fuel nozzle discharging into said annular chamber in a plane which is below the fuel level in said reservoir, and an air tube which communicates at its inner end with said annular chamber and has its inlet opening above the fuel level in said fuel reservoir.

7. In a carbureter, the combination with a constant level fuel reservoir, of a substantially vertical body tube which is open at its lower end, and is adapted for connection at its upper end with an internal combustion motor, an inner tube fitted within said body tube, there being between said tubes an annular chamber, and there being

a plurality of always open holes connecting said chamber with the interior of said inner tube in a plane above said fuel level, and there being an open duct connecting said fuel reservoir with said annular chamber, 70 and an air tube which communicates at its inner end with said annular chamber and has its inlet opening above said fuel level.

8. In a carbureter, the combination with a constant level fuel reservoir, of a substantially vertical body tube which is open at its lower end, and is adapted for connection at its upper end with an internal combustion motor, an ajutage fitted within said body tube, there being between said tube 80 and ajutage an annular chamber, and there being a plurality of ducts connecting said chamber with the interior of said body tube in a plane above said fuel level, and there being an open duct connecting said fuel 85 reservoir with said annular chamber, and a valve controlled air tube which communicates at its inner end with said fuel reservoir and has its inlet opening above said fuel level.

9. In a carbureter, the combination of a tubular body member, an ajutage fitted therein having in its outer surface an annular groove which forms with the body member an annular chamber, and having a 95 plurality of ducts through the wall of said ajutage communicating with said chamber, an air tube communicating with said chamber, and a fuel nozzle discharging into the chamber.

10. In a carbureter, the combination of a tubular body member, an ajutage fitted therein, having in its outer surface slightly below the plane of the restricted throat of the ajutage an annular groove which with 105 the outer body forms an annular chamber, and having a plurality of ducts extended obliquely downward from points within the ajutage just above the most restricted part of the throat thereof and communicating 110 with said groove, an air tube communicating at its inner end with said groove and extending therefrom at an inclination upward and being open to the atmosphere, a float chamber arranged to maintain the fuel 115 level slightly below the most restricted part of the throat of the ajutage, a fuel nozzle connected with said float chamber and extending at an inclination upward through the wall of the body and having its inner 120 end projected into the annular groove in the ajutage.

11. In a carbureter, the combination of a tubular body formed with a chamber and with an open air tube, an ajutage fitted in 125 said tubular body having an annular groove in its outer surface, which, together with the tubular body forms an annular chamber with which said air tube communicates, there being also a series of ducts through 130

the wall of the ajutage communicating with
said annular chamber, a fuel nozzle which
is secured in a hole in the wall of the body
and establishes communication between the
5 fuel reservoir and said annular chamber,
and a source of fuel supply connected with
said fuel reservoir.

In testimony whereof, I hereunto affix my
signature in the presence of two witnesses.

ANTOINE PROSPER PLAUT.
